UNITED STATES PATENT OFFICE.

ARTHUR F. BRIDGE, OF LOS ANGELES, CALIFORNIA.

PRESSURE-GAS HOLDER.

1,426,145.

Specification of Letters Patent. Patented Aug. 15, 1922.

Application filed April 21, 1921. Serial No. 463,245.

To all whom it may concern:

Be it known that I, ARTHUR F. BRIDGE, a citizen of the United States, residing at Los Angeles, in the county of Los Angeles, State 5 of California, have invented new and useful Improvements in Pressure-Gas Holders, of which the following is a specification.

This invention has to do with holders for the storage of gases under pressure; any 10 kind of gas in any kind of system. The invention, although not necessarily limited to such, has been developed particularly in view of fuel gas storage in connection with fuel gas distribution; and, as the invention 15 and its advantages may perhaps be most readily understood from a description of its specific adaptation and application to such uses, in the following specification a specific form of the invention will be so described, 20 however without limiting the invention in in its broader aspects. It will further be understood that one of the features of this invention is the provision of means for economically and effectively storing large quantities 25 of gas under pressure; the invention being applicable to large operations and large capacities.

The invention is designed, in the specific application herein spoken of, to overcome 30 certain difficulties which inhere in the present known type of gas holders used for fuel gas distribution. These holders are of two types, the well known telescoping tank type sealed with a water seal, and the ordinary 35 plain pressure tank. The telescoping tank type has the disadvantage that it is not capable, as economically constructed, to store gas under a pressure of more than a few ounces or so. In many gas distribution systems at 40 present the distributing system is operated at what is known as high pressure; that is a pressure of a pound or several pounds above atmosphere; so that it is necessary with these low pressure tanks to employ a compressor 45 plant (a pressure booster system) to take the gas out of the tank and put it into the distribution system. This of course entails the initial expenditure necessary for such a compressor plant and also the constant cost 50 of its operation.

On the other hand, although a plain tank can of course be charged with gas under pressure to any pressure which the tank will stand, its distinct disadvantage is due to the 55 fact that the tank can never be entirely emptied of gas; the capacity of the tank at

one atmosphere pressure always remaining therein.

It is a general object of this invention to provide a pressure gas holder which overcomes the difficulties hereinabove mentioned and which, among other features, is particularly adapted to large scale storage. Such objects and corresponding advantageous features will be best understood from a description of the specific and preferred form which this invention may take as applied to fuel gas distributing systems; and for that purpose a specific form of the holder is illustrated in the accompanying drawings, 60 65 70 wherein:—

The figure represents a vertical central section of the holder, together with such accompanying apparatus as may be used to fill and discharge the tank. 75

The holder according to this invention comprises mainly an upright steel cylindrical body 10 divided about midway by a horizontal partition diaphragm 11, and having a communicating pipe 12, preferably central, 80 which extends from partition 11 to the bottom of the tank and communicates with the chamber A above the partition and communicates at its lower end with the chamber B below the partition. For the purpose of 85 this last communication the lower end of pipe 12 may be perforated as indicated at 13. The pipe 12 may not only form the means of communication between two chambers but also may form a structural part of the tank 90 to assist in supporting the partition 11. Stay bolts 14 may also be used to support the partition 11 against the internal pressure; these stay bolts extending vertically between partition 11 and bottom 15 in the tank, tying 95 the bottom and the partition together.

The gas inlet and outlet to the tank may be located at 16 near the top of the lower chamber B. In the drawing this inlet is shown communicating by suitable pipe system with 100 a charging pressure regulator 17 and a discharging pressure regulator 18; the pressure regulator at 17 being the one through which the gas is put into the tank and the one at 18 being that through which the gas is taken 105 out of the tank.

As the initial step in the operation of this gas holder, the lower chamber B is entirely or substantially entirely filled with water. Gas is then forced in under pressure, gradually displacing the water from the lower chamber, this water rising through the com- 110

municating pipe 12 into the upper chamber A above diaphragm 11. When the lower chamber is filled to capacity with gas, all, or substantially all, of the water has then been forced into the pipe 12 and the upper chamber; and the pressure on the gas is then of course equal to the hydrostatic head above it. In charging the tank, pressure regulator 17 may be set to pass gas only up to the pressure of that maximum hydrostatic head; so that no manual attendance is required for filling the tank, once the pressure regulator has been properly set.

Pressure regulator 18 is set to deliver gas at the pressure required in the distributing system; say a pressure of one pound per square inch. As the gas discharges from the tank the water passes from the upper to the lower chamber, displacing the gas, until all or substantially all of the gas has been driven out under the hydrostatic head. Upper chamber A above diaphragm 11 may be made somewhat larger than the lower chamber B, so that, when practically all of the gas has been driven out, there will still remain in the upper chamber a sufficient head of water to create the desired pressure, for instance, one pound per square inch, to force out substantially all of the gas; and, as will be readily seen, the amount of pressure upon the gas as the last portion of it is being displaced from the tank, may be regulated and controlled by varying the total amount of water placed in the tank, thereby varying the amount of water which remains in the upper chamber when the gas is practically entirely displaced from the lower chamber. This amount of water may of course be so regulated, in consonance with the adjustment of outlet pressure regulator 18, as to not quite raise the water level in the lower chamber to outlet 16, to prevent water from being formed in that outlet. This can also be taken care of by a trap at 30.

Now there are many advantageous features in the system and construction herein described. The holder is self-protective; it cannot be filled beyond the pressure of the maximum hydrostatic head; because if more gas is forced in beyond that pressure, the gas will simply pass out through the perforations 13 and flow up through pipe 12 and through the body of water above.

Practically all of the gas may be discharged, as has been described; and may be discharged at a comparatively high pressure that serves to feed directly distribution systems without the necessity of any compressing plant.

The construction, and the relative placement of the body of water, reduces the net outward pressure on the top and bottom of the gas chamber; and the fact that the top and bottom of the gas chamber itself are fixed in relation to each other (in contra-

distinction to the relatively movable top and bottom of a telescoping tank) makes it possible to connect the top and bottom by stay-bolts, as described. It will be noted that the weight of water on top diaphragm 11 counterbalances a great part of the interior gas pressure; on the average, counterbalances about half of the interior gas pressure. This will be readily seen, without the necessity of further specific illustration, when it is noted that the hydrostatic head between upper water level L and lower water level L', (which is the hydrostatic head upon the gas in the lower chamber, and therefore the hydrostatic head pressing upwardly on diaphragm 11) is, at all times about twice the hydrostatic head between level L and the diaphragm 11. Consequently the hydrostatic head above diaphragm 11 opposes about half of the internal gas pressure. This circumstance materially reduces the required weight of metal and simplifies and cheapens the construction.

While the foregoing description is specific as applied to a typical form of this invention, it will be understood that the invention is not necessarily limited in its broader aspects to the specific preferred detail herein set out; and that the invention is not limited except as expressly so limited by the following claims which are to be read in their broad as well as their more specific interpretation.

Having described a preferred form of my invention, I claim:

1. A gas holder, embodying an upright shell, a horizontal partition across its central portion forming an upper water chamber and a lower gas chamber, means to admit gas to the lower chamber, and to withdraw gas from the upper part of the lower chamber under suitable pressures, an upright pipe in the lower chamber connected with the bottom and with the partition to form a stay connection between them and to form a support for the partition, and other stays extending between the bottom and partition to stay them substantially over their entire surfaces; the pipe having communication at its upper end with the upper water chamber and having communication at its lower end with the lower part of the lower gas chamber.

2. A gas holder, embodying an upright shell, a horizontal partition across its central portion forming an upper water chamber and a lower gas chamber, means to admit gas to the lower chamber, at a pressure substantially equal to the maximum hydrostatic head on the gas in said chamber when substantially all the water is displaced into the upper chamber, and to withdraw gas from the upper part of the lower chamber under a pressure substantially equal to the hydrostatic head when water in the lower

chamber rises to substantially the level of the outlet, an upright pipe in the lower chamber connected with the bottom and the partition to form a stay connection between them, and other stays extending between the bottom and partition to stay them substantially over their entire surfaces; the pipe having communication at its upper end with

the upper water chamber and having communication at its lower end with the lower 10 part of the lower gas chamber.

In witness that I claim the foregoing I have hereunto subscribed my name this 16th day of April, 1921.

ARTHUR F. BRIDGE.
